UNITED STATES PATENT OFFICE.

PETER BECK, OF RACINE, WISCONSIN, ASSIGNOR OF ONE-FOURTH TO MICHAEL JORGENSEN, ONE-FOURTH TO JOHN JORGENSEN, AND ONE-FOURTH TO JENIE BECK, ALL OF RACINE, WISCONSIN.

IRONING AND DRYING DEVICE.

Application filed December 13, 1919. Serial No. 344,659.

To all whom it may concern:

Be it known that I, PETER BECK, a citizen of Denmark, and resident of Racine, in the county of Racine and State of Wisconsin, have invented new and useful Improvements in Ironing and Drying Devices, of which the following is a description, reference being had to the accompanying drawings, which are a part of this specification.

10 The present invention relates to certain new and useful improvements in ironing and drying devices and has for one of its objects to provide a heated form for maintaining the garment to be dried or ironed in its normal shape until dried.

Another object of this invention is to provide means for maintaining a garment taut and in substantially its normal shape while heat is applied thereto whereby it is 20 quickly dried and ironed in the one operation, the drying of the garment while the same is taut taking the place of other devices formerly used in ironing garments.

A further object of my invention is to provide a device of the class and for the purposes stated which will have means for moistening a garment after the same has been placed on the form so that all creases therein will be removed before permitting 30 the garment to dry.

A still further object of my invention is to provide a device of the class and for the purposes described which may be employed in drying and ironing garments of various 35 shapes without changing the principles as illustrated in the accompanying drawings.

With the above and other objects in view, which will appear as the description proceeds, my invention resides in the novel construction, combination and arrangement of parts, substantially as hereinafter described and more particularly defined by the appended claims, it being understood that such changes in the precise embodiment of 45 the herein disclosed invention may be made as come within the scope of the claims.

In the accompanying drawings I have illustrated two complete examples of the physical embodiment of my invention constructed according to the best modes I have so far devised for the practical application 50 of the principles thereof, and in which:

Figure 1 is a front plan view of my device, illustrating the same in use for drying and ironing shirts or the like.

Figure 2 is a view part in section and part in elevation illustrating the structural details thereof.

Figure 3 is a sectional view taken there-through on the line 3—3 of Figure 2.

Figure 4 is an enlarged fragmentary sectional view taken on the line 4—4 of Figure 2, and

Figure 5 is a view part in section and part in elevation of a slightly modified form of my invention.

Referring now more particularly to the drawings, my device may be said to broadly consist of a garment receiving form, means for maintaining the garment taut while on the form, means for moistening the garment while taut on the form, if desired, to remove all creases therefrom, and means for heating the form to dry the garment, whereby the same will have the appearance of having been ironed.

The form consists of a body member 10 substantially elliptical in cross section and having a smooth exterior surface, a neck or collar portion 11, and two arms 12. The arms 12 are formed with inner rounded ends 13 having their sides flattened and fitted within recesses 14 formed at the shoulder portions 15 of the body and pivoted as at 16, in the manner to be later described.

The arms 12 are arranged to move in unison and each arm is connected with the upper end of a guide bar 17 by a link 18 having its upper end pivoted to the guide bar and its inner end pivoted to the arm as at 19. That form of my invention depicted in Figures 1 to 4, inclusive, is especially adapted for use in connection with shirts, or like garments 20, and for convenience in placing the garment on the form, I provide means 95 for normally urging the arms to a substantially vertical position, see dotted lines, Figure 2.

The arms are urged to such vertical position by means of an expansile spring 21 coiled about the lower portion of the guide rod 17, disposed within the steam or heating chamber 22, to be later described, and confined between the end of said rod and the

top intermediate wall 23 of the chamber 22. By this arrangement, the rod 17 is at all times normally urged downwardly and as the pivotal connections 19 of the links 18 are 5 inward of the arm pivots 16, the arms will be normally urged to their dotted line positions as shown in Figure 2. The outer ends of the arms 12 are provided with handles 24 for moving the arms against the action of 10 spring 17.

The means for maintaining the garment taut while being dried consists of side members 25 of somewhat T-shape and having the leg portions thereof disposed within elongated recesses 26 formed in the sides of the body 10, and arm stretching members 27 of similar shape and disposed within elongated recesses 28 in the under sides of the arms 12. The members 25 are normally urged outwardly of their recesses 26 by means of tension springs 29 secured to the members and engaging the bottom of said recesses. 15

The members 25 and 27 are adapted to be disposed in their recesses when the arms are 20 in vertical positions for convenience in placing a garment thereon and are adapted to be moved out of their recesses to draw the garment taut when the arms are moved from such vertical positions. As best shown in 25 Figure 2, the members 27 have their outer ends pivoted as at 30 to the arms and their inner ends pivoted as at 31 to the upper ends of the members 25 having their lower ends pivoted as at 32 in their recesses 26. 30

The pivots 32 of the members 25 work in elongated slots 33 to permit the necessary slight vertical movement of the members 25 when the arms are moved to vertical position. 35

40 Each arm 12 is connected with the opposite member 25 by means of a link connection 34 having its inner end secured to the arm as at 35 and its outer end pivoted to the opposite member 25 near its pivot 45 31 as at 36, so that when the arms are raised the links 34 will draw the upper end of members 25 and consequently the inner ends of members 27 inwardly, at the same time slightly moving the members 25 vertically. As the slots 33 are slightly outwardly and downwardly inclined the lower ends of the members 25 will also be moved inwardly 50 against action of springs 29.

The collar or neck portion of the garment 55 is made taut by means of two telescoping sleeve members 37 normally resiliently urged to expanded position by means of springs 38 disposed between them and the portion 11 of the form.

60 The body 10 is provided with a heating chamber 22 contacting with the exterior walls thereof and adapted to receive steam, hot air or any other desired heating medium through an inlet 39, and the heating medium 65 is communicated with the heating chamber

40 of the arms by means of a passageway 41 in its pivot 16 and is exhausted therefrom through passageway 41' in pivot 16.

As often times the garment may be partly dried and wrinkled or creased in spots when applied to the device, I provide a plurality of spray jets or openings 42 in the surface of the body 10 having a common supply pipe 43 so that the garments may be moistened before drying in order that the members 25 and 27 may draw the garment taut. The spray ejected from the jets 42 may either be steam, water or the like. 70 75

The garment 20 may be fastened on the form, if desired, by means of suitable retaining members, such as spring clips 43' as depicted in Figure 1. 80

In order to prevent the steam or other heating medium from escaping from the chamber 22 about the rod 17 where it passes through the wall 23, I enclose the lower end of the rod and the spring 21 with a cap 44. 85

In Figure 5 I have illustrated my device as modified for use in pressing or ironing trousers, and this form of my invention consists of a waist portion 45, two leg portions 46, and means 47 for drawing the trousers taut. The entire form is provided with a heating chamber 48 to which a suitable heating medium is supplied by supply pipe 49. 90 95

From the foregoing description taken in connection with the accompanying drawings it will be at once apparent that I provide novel means for quickly drying and ironing garments. 100

What I claim as my invention is:

1. An ironing and drying device comprising a form, an arm pivotally carried thereby, said arm being movable to a vertical position to permit the placing of a garment upon the form, means operable upon movement of the arm to a substantially horizontal position to draw the garment taut, and means for heating the form. 105

2. An ironing and drying device comprising a form, an arm pivotally carried thereby, means normally urging said arm to a substantially vertical position to permit the placing of a garment on the form, means operable upon the movement of the arm from its vertical position against the action of the urging means to draw the garment taut, and means for heating the form. 110 115

3. An ironing and drying device comprising a form, an arm pivotally carried thereby, means normally urging said arm to a substantially vertical position to permit the ready placing of a garment on the form, means operable upon the movement of said arm from its vertical position to draw the garment taut, means for moistening the garment, and means for heating the form to dry and iron the garment. 120 125

4. An ironing and drying device comprising a form, an arm pivotally carried by the 130

form, spring means normally urging said arm to a substantially vertical position so that a garment may be readily placed on the form, means for drawing the garment taut upon movement of said arm from its vertical position, and means for heating the form and arm to dry and iron the garment.

5. An ironing and drying device comprising a form, two arms pivotally carried by the form, means normally urging said arms to a substantially vertical position so that the garment may be readily placed on the form, means for drawing the garment taut upon movement of the arms from their vertical positions, and means for heating the form to dry and iron the garment.

6. An ironing and drying device comprising a form, two arms pivotally carried by the form, means normally urging said arms to a substantially vertical position so that a sleeved garment may be readily placed on the form with said arms within its sleeves, means for drawing the body of the garment and its sleeves taut upon movement of the arms from their vertical positions, and means for heating the form and the arms to dry and iron the garment.

7. An ironing and drying device comprising a form, two arms pivotally carried by the form, means normally urging said arms to a substantially vertical position so that a sleeved garment may be readily placed on

the form with said arms within its sleeves, means for moving said arms in unison, means for drawing the body of the garment and its sleeves taut upon movement of the arms from their vertical positions, and means for heating the form and the arms to dry and iron the garment.

8. An ironing and drying device comprising a form, two arms pivotally carried by the form, spring means connected with said arms to normally urge the same to a substantially vertical position so that a sleeved garment may be readily placed thereon with the arms in the sleeves thereof, means for drawing the sleeves, neck and body of the garment taut, and means for heating the form and arms to dry and iron the garment.

9. An ironing and drying device comprising a form, two arms pivotally carried by the form, spring means connected with said arms to normally urge the same to a substantially vertical position so that a sleeved garment may be readily placed thereon with the arms in the sleeves thereof, means for drawing the sleeves, neck and body of the garment taut, means for spraying the garment to moisten the same, and means for heating the form and arms to dry and iron the garment.

In testimony whereof, I affix my signature.

PETER BECK.
